UNITED STATES PATENT OFFICE.

WILLIAM KNIGHT, LATHROP, CALIFORNIA.

DOOR LATCH.

1,407,758.

Specification of Letters Patent. Patented Feb. 28, 1922.

Application filed December 6, 1920. Serial No. 428,461.

To all whom it may concern:

Be it known that I, WILLIAM KNIGHT, a citizen of the United States, residing at Lathrop, county of San Joaquin, State of California, have invented certain new and useful Improvements in Door Latches; and I do declare the following to be a full, clear, and exact description of the same, reference being had to the accompanying drawings, 10 and to the characters of reference marked thereon, which form a part of this application.

This invention relates to improvements in door latches, being adaptable for use in any place where a latch will be of service, although I feel that it is particularly adaptable for use on automobile doors, where a plain latch without actual lock and key means is ordinarily preferred.

20 The principal object of my invention is to provide a positive-working latch entirely free of springs and other delicate and sensitive parts, such as all other latches for this purpose employ, as far as I am aware, and 25 which sooner or later cease to function properly, especially under the severe and careless treatment generally accorded them in the automobile service.

Another object of the invention is to so 30 arrange the working parts of the device that the latch member itself need never be projecting from the door when the latter is opened, so that no relatively sharp member protrudes to catch and tear a person's clothing when entering or leaving the car.

35 A third object is to provide a readily removable member, the withdrawal of which will prevent the latch from being disengaged.

40 A further object of the invention is to produce a simple and inexpensive device and yet one which will be exceedingly effective for the purposes for which it is designed.

45 These objects I accomplish by means of such structure and relative arrangement of parts as will fully appear by a perusal of the following specification and claims.

50 In the drawings similar characters of reference indicate corresponding parts in the several views.

Fig. 1 is a perspective view of a portion of a door, showing my improved latch installed therein, a portion of the face-plate having been removed to show the parts back of the same.

55 Fig. 2 is a sectional elevation of the latch, showing the same in locked position with the door frame.

Fig. 3 is a similar view, showing the latch member disengaged from the door frame 60 and the door ready to be opened.

Fig. 4 is a similar view showing the position of the parts after the door is opened and moved away from the frame.

Fig. 5 is a fragmentary cross section taken 65 on a line 5-5 of Fig. 1.

Referring now more particularly to the characters of reference on the drawings, the numerals 1 and 2 represent the door and the 70 door frame respectively.

Arranged to be socketed into the door is a casing 3 constructed similarly to those at present used to contain latch mechanisms, and provided with a face plate 4 which fits flush with that edge of the door which lies 75 adjacent the edge of the frame 2.

Side grooves 5 are provided between the plate 4 and the adjacent edges of the casing 3, to receive an intermediate plate 6 therein, free to slide easily up and down, said plate 80 being provided with a vertical slot 7 adjacent its lower end to receive therethrough the outer end of a latch member 8 loosely pivoted in the casing 3, and counterweighted to fall by gravity when raised up to a pre-determined point about its pivotal connection.

85 A heavy smooth ball 9 is slidable on and supported by a split track 10 above the latch 8, this track sloping upwardly from 90 front to back of the casing and adapted to project through the slot 7, the latter being of sufficient width to allow of this.

95 The outer plate 4 is also slotted as at 11 to allow of the projection of the latch therethrough, this portion of the slot widening out from its lower to its upper end, and said upper end terminating in a circular portion 12 of a diameter smaller than that of the ball, so that the latter can only project part 100

way therethrough, said latter portion 12 being in alignment with the track 10.

Above the ball and loosely and pivotally mounted in the casing 3 is a segmental gear 13, the uppermost and outermost tooth of which engages the uppermost of a number of tooth-slots 14 cut in the plate 6 when the latter is in its lowermost position, the gear being suitably counterweighted as at 13 to retain it normally in the position just described. On the opposite end of the gear from the aforementioned outermost tooth is a handle 15 projecting through a curved slot 16 in the casing 3 and door 1, this slot being of course concentric with the pivotal connection of the gear, and being either on the inside or the outside of the door, or both.

A latch-socket 17 is provided in the frame 2, the shape of this socket from top to bottom being the same as that of the slot 11, except that the upper circular portion is omitted, the slot 17 terminating below the plane of such portion.

The operation of the device is as follows:—

Presuming the door to be locked as in Fig. 2, to release the latch the handle 15 is moved toward the edge of the door. This causes the plate 6 to be raised, and the lower end of the slot 7 therein bearing against the under side of the latch, the latter is raised out of the socket 17.

When thus raised to its fullest extent, the tip of the latch is just adjacent the ball, and is inwardly of the plane of the center thereof.

Then when the door is moved away from the door frame, the ball is free to roll downwardly and outwardly, on the outside of the latch-tip, as far as the limits of the orifice 12 will permit. Simultaneously, the handle 15 may be released, which will allow the gear and plate 6 to at once resume their original positions, owing to the action of gravity aided by the looseness of their mounting. At the same time the latch will still be held inactive by the ball, and will only be released to again fall into a locking position when the ball is moved inwardly to lie flush with the plate 6. This is accomplished automatically when the door is closed against the door frame, since the contact of the round surface of the ball with the edge of the door frame pushes the ball inwardly, causing it to rise at the same time owing to the angled track, and thus freeing the latch.

The seating of the latch is aided by the shape of the socket 17 and slot 11, and also by the loose journaling of the latch member, which allows considerable latitude of side movement at the beginning of its downward movement, which is gradually lessened to a snug fit in the socket when the latch finally comes to rest.

In order to provide a simple means for holding the latch locked, the pivotal pin of the door may if desired be in the form of a removable screw 18. By withdrawing this screw when the latch is locked, it will be seen that the gear cannot be rotated to raise the latch.

At the same time the gear cannot drop in the casing, since it is supported at one end by the plate 6 and at the other by the handle 15 bearing in the slot.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention, what I claim as new and useful and desire to secure by Letters Patent is:—

1. A door latch comprising a latch member pivotally mounted in the door and adapted to normally lie in a horizontal position and to then project from the door, means for raising the latch to lie in a substantially vertical position and inwardly beyond the edge of the door and an independent gravity-controlled member mounted above the latch and adapted to hold the same against resuming its normal locked position when the door is moved away from the door frame.

2. A door latch comprising a latch member pivotally mounted in the door and adapted to normally lie in a horizontal position and to then project from the door, means for raising the latch to lie in a substantially vertical position and inwardly beyond the edge of the door, a ball mounted in the door above the latch, and a face plate on the outside of the door provided with an orifice in alignment with the ball and through which the ball may partially protrude when the door is opened, said ball then dropping into said orifice ahead of the latch.

3. A door latch comprising a latch member pivotally mounted in the door and adapted to normally lie in a horizontal position and to then project from the door, means for raising the latch to lie in a substantially vertical position and inwardly beyond the edge of the door, a track in the door sloping upwardly from the outer edge thereof above the latch, and a ball on said track, said ball being arranged to roll downwardly ahead of said latch when the latter is raised and to prevent the same from resuming its locked position when the door is opened, the ball then projecting from the door.

4. A door latch including a latch member adapted to project into a door socket, a gear operatively connected to said latch and

adapted to be rotated to disengage the latch from the socket, and a removable pin forming the axis of said gear.

5. A door latch including a latch member adapted to project into a door socket, a gear operatively connected to said latch and adapted to be rotated to disengage the

latch from the socket, a removable pin forming the axis of said gear, and means whereby the gear will be maintained in proper alignment when the latch is engaged and the pin withdrawn. 10

In testimony whereof I affix my signature.

WILLIAM KNIGHT.
